CLAIM

The ornamental design for a folding pillow holder, as shown and described.

DESCRIPTION

FIG. 1 is a front perspective view of the folding pillow holder, showing my new design, in an state of use;

FIG. 2 is a rear perspective view thereof;

FIG. 3 is a front perspective view of the folding pillow holder in a closed state;

FIG. 4 is a rear perspective view thereof;

FIG. 5 is a top view thereof;

FIG. 6 is a bottom view thereof;

FIG. 7 is a right side view thereof;

FIG. 8 is a left side view thereof;

FIG. 9 is a rear view thereof; and,

FIG. 10 is a front view thereof.

1 Claim, 10 Drawing Sheets
